COLLAR

Adolf Closmann, Leipzig, Germany, assignor to
the firm Atlas Ago, Chemische Fabrik A. G.,
Leipzig, Germany

Application November 21, 1936, Serial No. 112,131
In Germany March 7, 1936

3 Claims. (Cl. 2—143)

The present invention relates to collars and particularly to collars made of paper, cardboard and similar materials, and to a process of making the same.

5 Collars which are made of materials that are easily subject to wear and tear, such as for example collars made of paper or cardboard, are usually reinforced at their front portions and the flaps where the two sides of the collar are 10 fastened together and secured to a shirt. The known constructions provide for this purpose suitable extensions of the front portions when the collar is cut or stamped out of the blank. These extensions are then folded back and glued 15 or otherwise secured to the inside of the collar separately for each individual collar, either manually or by machine, which requires considerable time and labor.

20 The object of the present invention is to overcome these disadvantages of the prior art, to facilitate the production of collars and to save time and labor in the manufacture thereof.

Another object resides in a new process of making collars, particularly collars made of paper 25 or like material.

A further object resides in producing a collar of paper or similar materials which resembles a collar of linen or the like to such an extent as not to be distinguishable therefrom.

30 Still another object consists in a method of finishing such collars along their cut edges by coating them with a layer of varnish or similar material.

These and other objects of the invention will 35 be fully described in the following detailed description and shown in the accompanying diagrammatic drawing in which

Fig. 1 discloses the various stages of manufacture of a collar according to the invention, while 40 Fig. 2 shows an end view of the collar in an intermediate stage of production.

According to the invention, a blank 2 is provided having a width exceeding the normal length of the collar in its final form 4 as indicated 45 in dotted lines in Fig. 1. The side portions 6 of blank 2, which preferably extend from points at or near the outer extremities 8 of the collar, are then coated on one face thereof with a thin layer of glue 10 or similar material, folded over 50 as shown in Fig. 2 with the layer of glue 10 toward the inside of the fold, and pressed against blank 2 so as to be permanently secured thereto. Thereafter, the collar 4 is cut out of the folded and glued blank 2, including button holes 12.

55 By this method of production a collar is ob-

tained which is produced entirely by machine and with less effort and within a shorter time than was possible by the known methods since each collar is not individually folded and glued into final form after being cut from the blank, 5 but a large series of collars are so finished either simultaneously or in continuous operation.

After the collars 4 have been folded, glued and cut from the blank 2, the cut edges 14 may be coated with a layer of varnish or similar 10 material whereby the paper, cardboard or the like of which the collars are made, is protected from splitting along the cut edges 14. Such a coating also serves to make the fact that the material is cut along edges 12 unnoticeable and 15 the edges 12 less conspicuous so that the collar which is made of cheap, substitute materials has the appearance of a normal collar made of linen or similar expensive materials.

It is obvious that the steps of folding the 20 portions 6, gluing them to the blank 2, cutting the shape of the collar 4 out of the blank, punching the button holes 10, and coating the cut edges 12 of the collar, provided this additional step appears necessary, are preferably performed 25 in one continuous operation by one and the same machine. However, it is also possible to execute the method in several operations by a series of machines. No matter which procedure is followed, the difficult and time-wasting operation of folding the reinforcing portions individually for each collar and then gluing them to 30 the rear sides thereof is avoided.

Also, as compared with the collars made by 35 previous methods, the collar according to the present invention is of neater appearance. When the reinforcing portions are folded and glued individually, the front edges of the collar are often uneven; while according to the present invention, the edges are sharply and cleanly cut.

40 While I have described herein one embodiment of my invention I wish it to be understood that I do not intend to limit myself thereby except within the scope of the appended claims.

I claim:

1. A method of producing paper collars which comprises folding over upon themselves the opposite edge portions of a paper blank which is wider than the length of a collar to be formed from the blank, adhesively securing such folded-over portions to the body of the blank, and cutting a collar from the blank thus formed with the ends of the collar located in the opposite folded-over portions.

2. A method of producing paper collars which

comprises providing a paper blank of a width extending the normal length of the collar, applying to the opposite edge portions of said blank which are to form the ends of the collar on one face thereof a layer of adhesive material, folding over the parts of the side portions which exceed the normal length of the collar, pressing said parts against said blank, and cutting a collar from the blank thus formed with the ends of the collar located in the opposite folded-over portions.

3. A method of producing paper collars which

comprises folding over upon themselves the opposite edge portions of a paper blank which is wider than the length of a collar to be formed from the blank and of a length at least equal to the width of a plurality of collars, adhesively securing such folded-over portions to the body of the blank, and cutting a plurality of collars from the blank thus formed with the opposite ends of each collar located in the opposite folded-over portions.

ADOLF CLOSMANN.
